UNITED STATES PATENT OFFICE.

IRA C. CATTON, OF BRIMFIELD, ILLINOIS.

RAILWAY-TIE.

1,118,909.

Specification of Letters Patent. Patented Nov. 24, 1914.

Application filed March 23, 1912. Serial No. 685,676.

To all whom it may concern:

Be it known that I, IRA C. CATTON, citizen of the United States, residing at Brimfield, in the county of Peoria and State of Illinois, have invented certain new and useful Improvements in Railway-Ties; and I do hereby declare that the following is a full, clear, and exact description of the invention, which will enable others skilled in the art 10 to which it appertains to make and use the same.

This invention relates to certain new and useful improvements in a railway tie and rail fasteners.

15 The invention relates particularly to a metal tie of a peculiar form and adapted at its ends to provide abutments for the rails and form a gage for the track, besides being of a form that will extend over considerable 20 area of the road bed to provide against lateral shifting motion of the track and provide a very firm support for said track.

One of the objects of the invention, therefore, is to provide a metal tie of peculiar 25 form, or a form in which its ends are recurved beneath the rail and then turned up at the inside of the rails to form a gage for the same. And an object, also, is to hold 30 the rail at that side by means of the tie only, in place of using spikes or other separate or special rail holding means.

A further object is to provide a tie having recurved ends and providing two portions to receive the same rail, the recurved 35 end of the tie being an integral part constituting a gage, the other portion also acting as a gage and slipped into place upon and held by the tie without other or separate securing means.

40 Besides this, the invention includes suitable fastening devices for the outer sides of the rails, one of them being adjustably secured on the tie.

Having pointed out the important objects, 45 others appearing later herein, I shall proceed to the description of the invention in detail, aided by the accompanying drawing, in which:

Figure 1 is a plan of one form of my railway tie showing the rails mounted thereon. Fig. 2 is a side elevation of the same. Fig. 3 shows a portion of the same in perspective. Fig. 4 is a plan of a slightly different shape of tie. Fig. 4^a shows, in perspective, a fas-

tening device for one side of the rail. Fig. 5 shows, in perspective, the underside of a certain form of an adjustable fastening device. Fig. 6 shows a portion of the tie in perspective and a portion of the fastener shown in Fig. 5 in connection therewith. Fig. 7 is an elevation of the tie in cross section, and the fastening device shown in Figs. 5 and 6. Fig. 8 shows, in perspective, a modified form of fastening device, and Fig. 9 is a cross sectional elevation of the tie 65 showing the fastener illustrated in Fig. 8 in connection therewith.

A indicates the tie which may be of several different shapes but two of which have been illustrated. The cross sectional form 70 of the tie is preferably that corresponding to what is known as an "I-beam". One of the forms of the tie is shown in Fig. 1 and resembles an S. Its extremities are recurved and separated the desired distance 75 from the main portion.

B B represent the rails lying across the recurved end portions and the body.

In Fig. 4 is a slightly different form of the tie consisting in this instance of a 80 straight body portion lying at right angles to the line of the rails, the recurved ends extending at opposite sides, as clearly shown, but other forms besides these two may be employed.

85 One of the main advantages of my tie is that the extreme ends, as plainly shown in Figs. 2 and 3 when split as indicated by broken lines in Fig. 2 may be bent up and down to serve certain ends. The line of 90 separation is in the vertical web of the I-beam preferably midway between the upper and lower flanges. One of these portions, the upper one indicated at C, is bent to an upright position and is then bent back to 95 overhang the tie while the other half of the I-beam may be bent downward into the portion D for certain purposes to be explained, but could also be left straight. By making the upturned portions C of the proper length and causing the distance between the two thus upturned ends to agree with the gage of the finished track these said portions 100 C are made thereby to serve as an automatic gage in constructing the track since it is 105 only necessary to lay the ties in position and place the rails upon them and against the said up-turned portions, after which

the fastening devices on the other portions of the tie can be put in position. In addition to the up-turned ends of the tie to serve as gages, I employ a device adapted 5 to be slipped into place in the tie which also assists in constituting a gage, for instance as shown in Fig. 4.

In the upper or top flange of the tie I 10 form a notch E which extends at an angle toward the central or upright web of the tie constituting what may be termed a "pocket." In Fig. 4^a is illustrated the fastening adapted for entering and seating in said notch. This consists of any usual upright portion 15 F to engage the vertical web of the rail, and a flat portion D to lie upon the top surface of the rail-base and tie, while H is an upright or vertical portion adapted to enter the said notch E. J is a flange at the lower 20 end of the part H parallel with the part D and which lies close to the underside of the said upper flange of the tie, it being understood that when this member is put in place it occupies the position shown in Fig. 4, the 25 inner face of the flange F lying in line with the extremity of the overturned part C, before described. Thus both the parts C and F form abutments for the rail, the said part E, in use, being practically a part of the tie. 30 In laying the track, the fastening member described is seated in the notch E and the rail brought against it as indicated in broken lines in said Fig. 4. It remains then to employ suitable adjustable fastenings at the 35 other side of the rail. As an example of what these fastenings may be and the manner of their attachment, I have provided Figs. 5 to 8. In Fig. 6 that portion of the tie shown in perspective is provided in and 40 slightly below its top surface with a series of transversely arranged saw teeth, or ratchet teeth, K, whose vertical portions face in the direction of the rail. Adjacent the said teeth is a hole K', elongated, and 45 lying parallel to the side of the tie and communicating with said hole is a notch K². In Fig. 5 is shown the form of fastening used with this arrangement of the tie. It comprises the upper flange portion L and the 50 horizontal portion M, the latter being extended into the part N whose underside is provided with teeth O to engage the teeth K of the tie. Depending from the part N is a portion P connected with the said part N by a narrow neck Q, the latter being shown 55 in section within the notch K² of the hole K'. It will be observed by a study of the figures last referred to that the fastening made up of the parts L, M, N, just described, 60 can be adjusted in the direction of the rail from tooth to tooth. The neck Q is substantially equal in length to the thickness of the upper flange of the tie through which it extends and in order to make this adjustment 65 the entire member must be shifted sidewise

outward so that the said neck will lie within the hole K'. This will permit the part P to be raised into the said hole so that the fastening can be moved in the desired direction to gain a tooth. The said neck is then moved back 70 into the notch K². A toothed key R, shown in Fig. 7, is inserted in the hole K' against the neck Q and part P and serves to prevent these parts from moving into the said hole K'. When the part P lies beneath the said 75 upper flange, as shown in Fig. 7, the entire fastener is prevented from vertical movement. The notch K² is sufficiently long to permit the neck Q to shift therein, to be adjusted from tooth to tooth, and at the same 80 time the part P is of such an extent that it cannot pass upward through said notch.

In Figs. 8 and 9 I show another form of fastener for the rail. The parts L' N' and O' correspond with L N O of said Fig. 5. Instead of employing the neck O and the part P there are two extensions S perforated as at T and these two extensions are designed to enter slots U in the top of the tie, see Fig. 4, and lie astride the vertical web of the tie 90 as shown in Fig. 9. There is a hole V in said vertical web and a key W extends through the said vertical web and the extensions S and serves to hold the fastener in position. It is adjusted by means of its 95 teeth O' to engage teeth in the top of the tie and this may be done after the key W is withdrawn. The replacing of the latter secures the fastener in the proper position, the hole V having sufficient extent to permit 100 movement of the key for the adjustment mentioned.

Any of these types of fasteners may be used or even others.

The provision of a tie of the forms shown or similar ones, that will extend over a large area is an important point since, as already stated herein, a larger support for the rails is thus presented and there is less likelihood of lateral movement of the track or sinking 105 of the tie in the road bed.

The downwardly extending parts D herein described and shown in Fig. 2 are used as gages when the tie is laid upon bridge girders for example, as X Fig. 2. These locate 115 the ties in the proper position since the said parts D can be dropped between the girders, the exact position of the tie being determined. Then, by placing the rails upon the ties those members are properly gaged and the work of securing them may proceed. A given amount of the whole track can then be laid in a fraction of the time required by the older methods.

The tie may be of other forms than those 120 shown and even a single straight body may be used so far as the upturned ends are concerned in which event the ends would lie against the outside surfaces of the rail instead of the inside and the fastening devices 125

would lie at the inside. The upturned portions could therefore be arranged for either side of the rail.

Having thus described my invention, I 5 claim:

1. As a new article of manufacture a railway tie having a recurved end and an upturned integral portion at said end to receive a rail and terminating at one side of 10 said place of the rail.

2. As a new article of manufacture a railway tie having recurved ends and integral upturned portions at said recurved ends providing abutments for the rails and terminating at the side of the place of said 15 rails.

3. As a new article of manufacture a railway tie having one end recurved upon the main portion for supporting the rail, the 20 recurved portion being upturned and terminating at the side of and overlying the base of the rail, and a fastening device carried by the tie at the opposite side of the place of the rail.

25 4. As a new article of manufacture, a railway tie having a portion recurved upon itself and upturned to engage the inner side of a rail, there being a recess in the top of said tie at the opposite side of the place of 30 the rail to receive a fastening device for said rail.

5. As a new article of manufacture, a railway tie having one of its ends bent or recurved upon itself in the same horizontal 35 plane, the extremity of the recurved portion being bent upward or recurved upon and overlying itself.

40 6. As a new article of manufacture, a railway tie having one of its ends bent or recurved in the direction of its opposite end, the extremity of said end being bent upward and recurved upon itself in the same vertical plane and overhanging its upper surface.

45 7. A railway tie having its ends recurved in the same plane with its body and in addition having the extremities of said ends recurved in planes perpendicular to the plane of the first described recurved portions and 50 overhanging themselves.

55 8. The combination with the rails of a railway track of a metal tie having its ends recurved in the direction of its opposite ends, and then again recurved upon themselves in planes perpendicular to the plane of the first described portions to form abutments for the rail, and fastening devices secured on the tie at the opposite side of the rails.

60 9. The combination with the rail of a track, of a metal tie having its ends recurved upon itself in a horizontal plane, both the body of the tie and the recurved portions

supporting the rails, the recurved portions then being recurved in a vertical plane their 65 ends forming abutments for one side of the rails, an opening in the top of the tie at the opposite side of the rail place, and a part seated in said opening to receive the rail and to form an abutment for the same. 70

10. The combination with the rails of a railway track, of a metal tie having its ends recurved upon itself, both the body of the tie and its recurved ends receiving and supporting the rails, the extremities of said 75 ends being recurved upon themselves to engage the inner sides of and form abutments for opposite rails, means seated on the body of the tie opposite the recurved abutments to also constitute abutments for the rails, 80 and fastening devices on the tie at the opposite side of the rails.

11. A railway tie having its ends recurved upon itself and lying in the same plane, both the body of the tie and the recurved 85 portions receiving and supporting the rails, the said portions being again recurved to overhang the inner side of the base of the rails, a fastening device on each recurved portion at the opposite side of the rails, and fastening devices at both sides of the rails upon the main or body portions of the tie. 90

12. A railway tie having recurved ends lying in the same plane with the body of 95 said tie, the extremities of the ends being again recurved to overhang themselves and overlie the inner side of the rails, each of the ends having an integral downwardly extending portion perpendicular to the plane of the tie. 100

13. A railway tie having recurved ends lying in the same plane with its body, the extremities of said ends being divided into two extensions, one of them being bent upward and the other downward, the upper 105 one being bent toward and adapted to receive the rail against it, for the purposes set forth.

14. An I-shaped railway tie including two abutments for a rail, one end of the tie being recurved in the same plane with the body to receive the rail and also being recurved at its end to overhang the base of the rail to form one of said abutments, there being a notch or recess in the body of the tie 110 adjacent that side of the rail which the recurved part overhangs, said notch or recess extending away from the rail-place and terminating in a pocket to receive a part constituting the other of the abutments. 115 120

In testimony whereof I affix my signature, in presence of two witnesses.
